CENTRIFUGAL SPEED RESPONSIVE
DEVICEHerbert L. Bone, Forest Hills, Pa., assignor to
Westinghouse Air Brake Company, a corpora-
tion of Pennsylvania

Application November 27, 1945, Serial No. 631,161

3 Claims. (Cl. 264—15)

1

My invention relates to speed responsive devices.

One object of my invention is to provide a speed responsive device which can be mounted adjacent to and driven from the end of an axle of the pony truck of a locomotive.

Another object of my invention is to provide in a speed responsive device a pivotal mounting for the centrifuge members of the device whereby the critical clearance between the centrifuge members and the cooperating push rod of the device may be accurately and easily adjusted.

According to one form of my invention the device comprises a main housing which is adapted to be bolted to the outer end of a wheel or an axle of the pony truck of a steam locomotive in axial alignment therewith in such manner that the housing will rotate with the axle. Pivotedly supported inside of the housing on pivot pins which extend at right angles to, and are equally spaced from, the longitudinal axis of the housing are two similar centrifuge members. These centrifuge members are each formed with a weight arm extending parallel to the axis of the housing, and with an operating arm extending radially toward the axis of the housing, and are each provided at the inner end of the operating arm with a gear tooth which extends into and cooperates with a recess formed in a push rod. The push is guided by means of suitable guide bearings for longitudinal sliding movement within the housing, and is biased by means of a compressed coil spring to the longitudinal position in which the weight arms of the centrifuge members occupy their inner extreme positions, whereby when the axle is rotating the resultant centrifugal force will tend to move the push rod from one extreme position to another. In order to provide the proper clearances to reduce wear to a minimum in the toothed connection between the centrifuge members and the push rod, the pins which support the centrifuge members are mounted at their ends in eccentric bushings so arranged that by rotating these bushings the clearances in the toothed connections can be readily increased or decreased.

Other objects and characteristic features of my invention will become apparent as the description proceeds.

I shall describe one form of speed responsive devices embodying my invention, and shall then point out the novel features thereof in claims.

In the accompanying drawings, Fig. 1 is a vertical longitudinal sectional view showing one

2

form of speed responsive device embodying my invention.

Figs. 2 and 3 are detail views of a bushing 30 forming part of the speed responsive device illustrated. Figs. 4 and 5 are detail sectional views taken substantially on the lines IV—IV and V—V, respectively, of Fig. 1.

Similar reference characters refer to similar parts in each of the several views.

10 Referring to the drawings, the speed responsive device in the form here shown comprises a main housing 1 and an auxiliary housing 2. The main housing 1 is closed at one end by an end plate 3 secured in place by machine screws 4, and is adapted to be mounted on the end of a car or locomotive axle, such as a pony truck axle 5 by means of a plurality of bolts 6 which pass through clearance holes in the housing and are screwed into threaded holes 7 formed in the pony wheel 8 mounted on the axle. It will be apparent, therefore, that when the wheel 8 and axle 5 rotate, the housing 1 will rotate therewith. For reasons which will be obvious, it is desirable to maintain the housing 1 in concentric relation to the axle 5, and to this end the end plate 3 is provided with an annular projection or rib 9 concentric with the housing, which rib extends into and cooperates with a concentric recess 10 machined in the end of the axle.

30 A pair of ball bearings 11a and 11b are fitted within counterbores 12a and 12b formed in a bearing opening 12 provided in the outer end of the main housing 1, and the inner races of these bearings snugly receive a tubular extension 13 formed on the auxiliary housing 2. The bearings 11a and 11b are spaced apart in the bearing opening 12 by means of shoulders 12c and 12d formed at the inner ends of the counterbores, and on the tubular extension 13 by a spacing sleeve 14 having the same length as the distance between the shoulders 12c and 12d. The outer race of the bearing 11b is secured in place in the counterbore 12b by a bearing retainer 15 (see Fig. 5) bolted to the main housing 1. The inner races of the bearings are secured to the tubular extension 13 by a nut 16 screwed onto the threaded inner end of the tubular extension 13. The nut 16 is locked in place by a lock washer 17. The space between the bearings is packed with a suitable lubricant, and a felt oil seal 18 is provided to protect the outside bearing 11a from dirt and moisture. A cable connection (not shown) which extends 50 from the housing 2 to the locomotive frame,

serves as a torque arm to prevent the auxiliary housing from rotating when the main housing is rotated in response to rotation of the axle 5. It will be apparent, therefore, that the auxiliary housing 2 remains stationary at all times.

This feature of my invention is fully illustrated and claimed in my divisional application, Serial No. 214,392, filed on March 7, 1951, for Speed Responsive Devices.

The main housing 1 houses a centrifuge assembly, while the auxiliary housing 2 houses a contact assembly, the contacts of which are operated by the centrifuge in response to changes in the speed of rotation of the axle 5.

The centrifuge assembly in the form here shown comprises two centrifuge members 20 and 21 pivotally supported on pivot pins 22 and 23 which extend at right angles to, and are equally spaced from, the longitudinal axis of the housing 1. The centrifuge members are each formed with a curved weight arm which extends parallel to the axis of the housing 1, and with an operating arm which extends radially toward the axis of the housing. The operating arms are provided at their inner ends with gear teeth 20a and 21a, respectively, which gear teeth extend into and cooperate with tooth openings 24a formed in a rectangular portion 24b of a push rod 24. The push rod 24 is slidably supported at one end in a bearing bushing 25 mounted in the end plate 3, and at the other end in a bearing bushing 26 mounted in the end of a tubular push rod guide 27 bolted to the end plate 3 by means of studs 28 (see Fig. 4). A compressed coil spring 29 surrounds the push rod between a shoulder 27a formed in the guide 27 intermediate its ends and an annular flange 24c provided on the push rod, and constantly biases the push rod to the longitudinal position in which the rectangular portion of the push rod abuts against the flanged end of the bearing bushing 25. The parts are so proportioned that when the push rod occupies the position to which it is biased, the weight arms of the centrifuge members 20 and 21 will be rotated to their inner extreme positions, and it will be apparent, therefore, that when the centrifuge assembly is rotated in response to rotation of the axle 5, the weight arms will tend to fly outwardly and will thereby move the push rod toward the left as viewed in Fig. 1. The extreme left-hand position to which the push rod is free to move is limited by engagement of the annular flange 24c with a stop surface 27b provided on the push rod guide 27.

In order to prevent excessive wear in the toothed connection between the centrifuge members and the push rod it is essential to be able to reduce clearances between the gear teeth and the associated tooth openings to a minimum and to this end the pivot pins which support the centrifuge members are supported at their ends in eccentric flanged bushings 30 (see Figs. 2, 3 and 4) rotatably mounted in bushing openings 31 provided in spaced laterally extending lugs 32 formed on the end plate 3. The flanged bushings are adapted to be secured in adjusted positions by means of screws 33 which pass through clearance holes in the flanges and are screwed into tapped holes in the lugs 32, and in order to facilitate adjusting the bushings to the desired angular positions relative to the lugs each bushing is provided with twelve holes spaced 30° apart (see Fig. 2), while each lug is provided with two pairs of tapped holes the holes of each pair of which are spaced 45° apart. With the

holes arranged in this manner it will be obvious that by inserting the screws through the proper holes the bushings may be readily rotated to a variety of angular positions spaced 15° apart. It will also be apparent that since the bushings are eccentric, rotation of the bushings will cause the operating arms to move toward or away from the push rods an amount equal to the eccentricity of the bushings which eccentricity is sufficient to take care of any normal amount of adjustment that may be necessary to prevent wear between the gear teeth and the tooth openings.

Since the centrifuge assembly rotates about a horizontal axis, the gravitational force acting on the centrifuge members is reversed with respect to the centrifugal force acting thereon twice during each revolution of the assembly. At slow speeds, when the gravitational force is greater than the centrifugal force, this reversal of the gravitational force will cause the centrifuge members to reciprocate radially as the assembly revolves, if there is any clearance between the gear teeth 20a and 21a and the tooth openings 24a. The adjustable bushings 30 provide a means for reducing the gear tooth clearance to a point where this reciprocating action and the resulting wear are substantially eliminated.

The pivot pins 22 and 23 are held in place in the bushings by means of end plates 35 clamped in place by means of the same screws which secure the bushings to the lugs. The end play of the centrifuge members is controlled by shims 36 inserted between the flanges of the bushings and the associated lugs. These shims are of the laminated type and are peeled to the proper thickness to provide the desired end play.

The left-hand end of the push rod 24 is provided with an antifriction thrust assembly comprising bearing cup 40 screwed onto the threaded end of the rod and locked in place by means of a lock washer 41 and a jam nut 42. A ball bearing 43 is secured within the outer end of this bearing cup by peening over the outer edge of the cup, and the inner race of this bearing receives the rounded end 44a of a U-shaped thrust member 44 the arms 44b of which straddle with some clearance a tappet guide 45 secured by means of screws 46 to the inner side of the right-hand wall of the auxiliary housing 2 as viewed in Fig. 1. The yoke of the U-shaped thrust member bears against one end of a tappet 47 the outer end of which is slidably mounted in a sleeve 48 pressed into the tappet guide 45. The free end of the tappet 47 engages a hardened steel bar 49 secured to an insulating member 50 which latter in turn is riveted to a plurality of movable contact fingers 51, 52, 53 and 54, respectively. The movable contact fingers are adapted to cooperate with fixed contact fingers (not shown) secured within the auxiliary housing 2, the movable and fixed contacts within the auxiliary housing forming a circuit controller as fully described and claimed in my aforesaid divisional application filed on March 7, 1951, for Speed Responsive Devices.

In order to permit readily inspection of the contacts and adjustment when necessary, the outer end of the auxiliary housing 2 is closed by a removable cover 53.

The operation of the governor as a whole will be readily understood from an inspection of the drawing and from the foregoing description without the necessity for further detailed description.

Having thus described my invention, what I claim is:

1. In a speed responsive device comprising a member which is adapted to be rotated at different speeds, a push rod supported for longitudinal sliding movement between two extreme positions at the axis of rotation of said member, spring means biasing said push rod to one extreme position, centrifuge members carried by said first mentioned member and operatively connected with said first mentioned member by toothed connections for moving said push rod to another longitudinal position in response to rotation of said first mentioned member, the combination of adjustable means for pivotally attaching said centrifuge members to said first mentioned member, said means comprising pivot pins mounted at their ends in eccentric bushings rotatably mounted in spaced legs provided on said rotatable member, whereby by rotating said bushings the clearances in said toothed connection can be readily varied, and means for clamping said eccentric bushings in adjusted positions.

2. In a speed responsive device comprising a member which is adapted to be rotated at different speeds, a push rod supported for longitudinal sliding movement between two extreme positions at the axis of rotation of said member, spring means biasing said push rod to one extreme position, two centrifuge members pivotally supported on pivot pins which extend at right angles to and are equally spaced from the axis of said first mentioned member, each said centrifuge member comprising a weight arm extending parallel to the axis of rotation of said first mentioned member and an operating arm extending radially toward said push rod, each said operating arm being provided with a tooth which extends into a recess provided in said push rod, whereby movement of said centrifuge members due to rotation of said first mentioned member will move said push rod in opposition to its bias, the combination of mounting means for said pins comprising spaced lugs secured to said first member, eccentric bushings rotatably mounted in said lugs and receiving the ends of said pins, flanges on said bushings provided with a plurality of spaced holes, screw threaded holes in said lugs spaced apart different distances from the holes in said flanges, and screws extending through selected ones of the holes in said flanges and screwed into selected ones of said screw threaded holes.

3. In a speed responsive device comprising a

member which is adapted to be rotated at different speeds, a push rod supported for longitudinal sliding movement between two extreme positions at the axis of rotation of said member, spring means biasing said push rod to one extreme position, two centrifuge members pivotally supported on pivot pins which extend at right angles to and are equally spaced from the axis of said first mentioned member, each said centrifuge member comprising a weight arm extending parallel to the axis of rotation of said first mentioned member and an operating arm extending radially toward said push rod, each said operating arm being provided with a tooth which extends into a recess provided in said push rod, whereby movement of said centrifuge members due to rotation of said first mentioned member will move said push rod in opposition to its bias, the combination of mounting means for said pins comprising spaced lugs secured to said first member, eccentric bushings rotatably mounted in said lugs and receiving the ends of said pins, flanges on said bushings provided with a plurality of spaced holes, screw threaded holes in said lugs spaced apart different distances from the holes in said flanges, screws extending through selected ones of the holes in said flanges and screwed into selected ones of said screw threaded holes, shims interposed between said flanges and said lugs, and end plates closing the ends of the openings in said bushings secured in place by said screws, said shims and end plates serving to position said centrifuge members longitudinally on said pins.
